Daniel Levi, Chicago, Ill., assignor to Gamble
Brothers, Incorporated, Louisville, Ky., a corporation of Kentucky

Application March 18, 1940, Serial No. 91,034

Term of patent 3½ years

To all whom it may concern:

Be it known that I, Daniel Levi, a citizen of the United States, residing at Chicago, in the county of Cook and State of Illinois, have invented a new, original, and ornamental Design for a Desk and Seat Unit, of which the following is a specification, reference being had to the accompanying drawing, forming a part thereof.

I claim:

The ornamental design for a desk and seat unit, substantially as shown.

DANIEL LEVI.
